L. LEFFORGE

FARM FENCE

Filed Dec. 15, 1927

UNITED STATES PATENT OFFICE.

LAWRENCE LEFFORGE, OF WABASH, INDIANA.

FARM FENCE.

Application filed December 15, 1927. Serial No. 240,184.

This invention relates to the construction of a farm fence with shorter posts than now in general use supporting a woven wire strip next to the ground from 26 to 32 inches high, through which hogs and sheep cannot pass, said fence having a plurality of strands of barbed wire above the woven wire to keep large hogs, horses and cattle from jumping over or climbing the fence.

10 The object of the invention is to provide barriers which will adequately prevent larger animals from breaking down the woven wire fence by leaning on it or by pawing or striking it with their feet, and also to make 15 the barriers adjustable that they can be turned out of the way and the barbed wire so lowered that a team can get close to it at the end of the row with their heads and necks and the end of a cultivator tongue 20 swung over the fence at the turns, in order that cultivation may be extended closer to the fence than has been heretofore possible and to make climbing the fence by a person less difficult when absence of stock on either 25 side of the fence renders the elevation of the arms and barbed wires unnecessary.

A further object is to secure the above advantages in a fence that will cost little or no more in the aggregate than farm fences now 30 in general use and which will be easier to stretch and to anchor.

I accomplish the above and other objects which will hereinafter appear by the means illustrated in the accompanying drawing, in 35 which—

Fig. 1, is a perspective view of a section of a farm fence embodying my invention.

Fig. 2, is a vertical section through the center of the upper end of a post showing the 40 mechanism for adjustably attaching the barbed wire supporting arms.

Fig. 3, is a vertical section on the line 3—3 of Fig. 2, and

Fig. 4, is a section on the line 4—4 of 45 Figs. 2 and 3.

Like characters of reference indicate like parts in the several views of the drawing.

The fence post 5 illustrated in the drawing is of usual tubular iron, having any suitable 50 base, not shown. As many of these as are desired or required are set in the ground the usual distances apart and form the supports for a strip 6 of woven wire of usual mesh, mostly 26 inches high, but this can be varied without departing from my invention. The

woven wire is fastened to the posts by staples 7 in the well known manner.

A hole formed through the post near its upper end receives a bolt 8. The bolt head 9 may contact the post directly or a washer 10 may be interposed between the head and the post, and the side of the washer next to the post is preferably curved to conform with the shape of the post. Mounted on the bolt on the opposite side of the post from head 9 is a casting having a curved surface to fit the post on its side next to the post, and an adjacent annular face at right angles to the bolt, from the middle of which is an extension 12, making a square shoulder with the annular face. The extension 12 is long enough to form a bearing for a plurality of arms 13, here shown as three in number. The sides of the extension are polygonal in shape to fit correspondingly shaped holes in 75 the arms, the polygonal shape being for the purposes for allowing the angular positions of the arms to be changed and for holding the positions of the arms when changed. A nut 14 screws on the threaded end of the bolt 80 8. A washer 15 between the nut and adjacent arm-ends enables the arm-ends to be tightened by screwing the nut on the bolt.

The polygonal shape of the extension 12 allows each arm to be set at eight different 85 positions, including vertical above and vertical below the bolt horizontal on two sides and at 45° between any two of the previously mentioned positions.

Each arm 13 has an end notch 16 in which a barbed-wire 17 is seated, and near the end of the notch is a hole through which passes a wire 18, the ends of which are brought around the adjacent barbed-wire and are twisted together to tie the wire 17 in its seat. The ends of the tie wire are preferably left 90 projecting to act as additional barbs at the tie.

It is often desirable to attach an additional barbed-wire 19 to an arm between the 100 pivot and outer end of the arm and for that I provide an intermediate notch 20 with its adjacent hole for the insertion of a tie-wire.

In the operation of my invention one of the arms 13 at each post of the fence is set 105 in vertical position above the bolt 8, which presents its top barbed wire 18 in place of the top wire above the usual four foot woven wire fence, and where a 26 inch high woven wire strip is used, the vertical arms prefer- 110

ably support a second barbed wire 19. The other two arms 13 at each post are assembled in horizontal positions opposite each other and at right angles with the line of fencing.

5 Each of these arms helps to support another barbed wire 17—that is, two more barbed wires placed on opposite sides of the fence, where they are supported by attachment to the ends of the arms 13 of their respective 10 sides of the fence. The arms hold these last wires away from the fence at a distance equal to the lengths of the arms, and the purpose is to form barriers at those distances to keep horses and cattle from 15 approaching any closer to the fence, and therefore to keep the animals from leaning against the fence in their efforts to reach a few mouthfuls of food on the opposite side.

20 When it is desired to drive a team close to the fence as at the end of a row in plowing or cultivating, the nuts 14 are run off of bolts 8 far enough to allow the arms 13 to be slipped off of the polygonal extensions 25 12 whereupon the outer ends of the arms and the wires carried by them can be dropped down beside the fence to positions below the top of the woven wire 6.

In localities where three arms are not 30 needed, as along a highway, one arm may be omitted and its place spaced out by a washer of equal thickness, not shown.

The saving from the use of shorter posts 35 and lower woven wire members balances the cost of the arms and their attachment means, and the reduction in height in the woven fencing and posts makes the stretching and anchoring of the fence less difficult.

40 While I have here shown and described the best form of my invention now known to me it is capable of modification in many respects without departing from the spirit of the invention. I therefore do not desire to be limited to the exact materials, forms 45 and arrangements shown, any more than is required by the appended claims.

I claim:

1. In a fence, a series of posts, a plurality 50 of arms for each post, a bolt for each post passing through the post and its group of arms, a member between the bolt and arms

having out-of-round sides which fit in correspondingly shaped openings in the arms, means to keep the last member from rotating on the bolt, means on the bolt to 55 clamp the arms together and wires extending longitudinally of the fence supported by the arms.

2. In a farm fence, a series of posts set 60 in the ground, a plurality of arms for each post, a bolt for each post passing through the post and its group of arms and projecting past the arms, a member between the bolt and arms having polygonal sides fitting in correspondingly shaped openings in the arms 65 and having a curved end conforming to and contacting the post, means comprising a nut on the projecting end of the bolt to clamp the members together, and wires supported by the arms and extending longitudinally of the fence.

3. In a farm fence, a series of posts set 70 in the ground, a plurality of arms for each post two of which are normally in horizontal position and one in vertical position, a bolt for each post passing through the post and its group of arms whereby the arms radiate around the bolt, a member through which the bolt passes having a curved face conforming with and contacting the post and having an extension polygonal in cross section passing through the arms, the arms having corresponding openings to receive the extension, a nut on the bolt, a washer between the nut and group of arms and fence wires supported by the arms and adjustable in 80 height and position by swingingly adjusting the arms.

4. In a fence, a series of posts, a plurality 85 of arms for each post, a bolt for each post passing through the post and its group of arms, a member between the bolt and arms octagonal in cross section fitting in correspondingly shaped openings in the arms said member having a face contacting the post shaped to engage the post and prevent rotation of the member on the bolt, means on the bolt to clamp the arms together and wires extending longitudinally of the fence supported by the arms.

In testimony whereof I affix my signature.
LAWRENCE LEFFORGE.
